UNITED STATES PATENT OFFICE.

HARRY A. CUMFER, OF CHICAGO, ILLINOIS, ASSIGNEE OF ONE-HALF TO ALBERT D. STEWART, OF HUTCHINSON, KANSAS.

PROCESS OF FORMING A CORRUGATED BOARD AND PRODUCT PRODUCED THEREBY.

Application filed March 22, 1923. Serial No. 626,759.

To all whom it may concern:

Be it known that I, HARRY A. CUMFER, a citizen of the United States, residing in the city of Chicago, county of Cook, and State of Illinois, have invented certain new and useful Improvements in Processes of Forming a Corrugated Board and Product Produced Thereby, of which the following is a specification.

10 This invention relates to improvements in a corrugated board, and relates more particularly to a process in which separate sheets are fed continuously to a machine, one of which is corrugated as it passes therethrough, and is fixedly united or annexed to the lower base sheet to form a relatively rigid and unitary structure.

This invention is in part a continuation of previous applications Serial Numbers 20 504,289 filed September 30th, 1921, which has matured into Patents 1,525,071 and 582,344 filed August 17th, 1922.

Among the salient objects of the invention are to provide a corrugated sheet and process of making same, whereby separate sheets are combined or fixedly united to each other, one of said sheets comprising a base portion, and the other a corrugated element fixedly amalgamated to the base, said sheets being produced continuously and severed to any predetermined desired sizes; to provide a corrugated structure in which perforations or depressions of any desired configuration may be made in the corrugated portions to facilitate the fixing of a plastic substance to the face of the sheet when utilizing the corrugated sheet as lath elements; to provide a structure which may be used for innumerable purposes such as boxboard, partitions for packing cases, bottle cases, and innumerable other uses; to provide a structure which is relatively cheap to construct, and one which is readily applicable to innumerable industrial uses, and purposes.

45 Fig. 1 is a side elevational view of the apparatus. Fig. 2 is a plan view of the machine shown in Fig. 1. Fig. 3 is an enlarged detail of the corrugating mechanism and sheet combining portion of the machine. Fig. 4 is a modified method of forming perforations in the corrugated portions of the sheet. Fig. 5 is an enlarged detail view showing the slitting of the corrugated portions in the preferred method of producing the sheet. Fig. 6 is a view of a portion of

the sheet formed by the preferred method, and Fig. 7 is a perspective of a portion of the sheet formed by the modified method of perforation. Fig. 8 is an enlarged detail view of the cutting knives used in the preferred method. Fig. 9 is a sectional view taken along the line 9—9 in Fig. 6, and Fig. 10 is a view taken along the line 10—10 in Fig. 7.

Referring to the drawings, and briefly explaining the method of producing the product, separate sheets 1 and 2 are fed from rolls mounted on reels shown diagrammatically at 3 and 4 respectively. The two sheets are fed into the machine, the lower sheet being passed through an adhesive coating bath shown at 5 while the upper sheet is corrugated in a manner shown in Fig. 3, and cut, as shown.

The lower and upper sheets are then united and pressed together to form a unitary structure which is passed on to a punching mechanism which presses the slit portions into depressions shown in Fig. 6, these depressed portions adhering to the lower adhesive coated sheet. The sheet is then passed on and cut in any desired lengths.

Describing now more in detail the method employed for making the corrugated plaster board, which has a waterproof base of relatively stiff stock known as chip-board, and having applied thereto a corrugated sheet which is perforated along the top of the raised corrugations as shown in Fig. 6 in order that a plastic substance such as plaster will adhere thereto, the portions of the plastic covering being forced in behind the edges of the apertures to produce the keying effect, and causing the plaster to more fixedly adhere to the plaster board.

The details of this construction are brought out most clearly in Figs. 6 and 7.

Referring to the drawings, the upper sheet 2 passes from the reel under the guide roll 6 and between the lower corrugating roll 7 and upper corrugating roll 8 upon the periphery of which is carried a corrugating belt which comprises cross bars 9 united by chain links 10. These cross bars register with the teeth of the lower corrugating roll 7 while the sheet 2 is fed therebetween and receives a corrugated zigzag deformation. After passing through the corrugating rolls the formed sheet is carried along with the corrugating belt, the

bars 9 continuing to remain in registration with the formed corrugations, thus preventing the sheet from stretching out due to the tension produced by its being fed forward through the machine. The corrugated sheet then passes between the slitter roll shown at 11 which has fitted upon its outer surface a plurality of cutting knives 12 in the form of the letter H, such as that shown in Fig. 8. These knives are arranged to produce cuts in the sheet such as that shown in Fig. 5 at 13, and alternately positioned along the top of the corrugation as shown in Fig. 6. The knives contact with lugs 14 on the upper roll 15. After cutting or slitting in this manner, the sheet proceeds with the endless corrugating belt.

It will be noted that the slitting of the corrugation takes place upon the portions 20 between the corrugated bars as the sheet proceeds.

The lower sheet fed from the reel 3 passes over the guide rolls shown at 16, 17 and 18, after which it is immersed in a bath of adhesive material shown at 5 by means of an immersing roll 19 vertically adjustable by means of the handle 20.

After passing through the bath of adhesive material, which may consist of asphalt, 30 or bitumen of different character, pitches, sizes or adhesive siliceous substances, or any other type of adhesive material which will fixedly unite and combine the corrugated upper sheet with the lower base sheet.

After passing through the bath, the sheet 35 is directed between doctor blades shown at 21 where the excess adhesive substance is scraped from the surface of the sheet. The sheet is then fed onto the belt 22 which is fed 40 through a tank or vat 23 containing water or powdered non-adhesive material which prevents the adhering of the coated sheet 1 to the belt. Under certain conditions water will suffice as a proper non-adhesive 45 medium and under other conditions a powdered material such as graphite, talc or other powdered substance proves more satisfactory.

The lower sheet 1 and the corrugated sheet 50 2 are then pressed together between the press rolls 24 and 25, proceeding then with the endless corrugating belt along the supporting table 26 to the punching roll 27 which has positioned therebeneath a 55 roll 28 which supports the sheet during the punching operation.

Upon the surface of the punching roll are members 29 which register with the slitted or cut portions of the corrugation. The function 60 of these punching members 29 is to depress the free ends 13^a and 13^b shown in Fig. 5 so that they adhere to the lower sheet as shown in Fig. 6. This produces a plurality of depressions designated as 13^c in Fig. 6, the adhering of the free ends 13^a and 13^b

to the lower sheet producing a more rigid structure than would be formed by perforations as shown in Fig. 7.

These depressed portions not only produce a more rigid construction but also incorporate the advantages of the perforations due to the fact that the plastic substance applied to the surface of the corrugated sheet shown in Fig. 6 has much the same keying effect that it would have with the perforations shown in Fig. 7, as the plastic material seeks its way beneath the side edges of the depression and underneath the raised or corrugated ridges. This is similar to the effect that the plaster substance has with the apertures shown at 30 in Fig. 7, and the rigidity as explained, is improved by the fact that the slitted portions 13^a and 13^b are fixedly united to the lower sheet.

After passing the punching roll the sheet is severed by means of a cutting roll 31 which has on its surface a blade or severing knife 32 rotated in a manner to produce the proper length units. Two or more blades may be provided according to the size of the sheet and the rapidity of rotation.

In Fig. 1 at 33 are shown hand wheels which are used to regulate the machine upon the separate sets of rolls positioned below.

The entire structure is mounted upon frame members 34 and the parts are combined to operate as a single unit. It is essential that the rolls function in timed relation and for this reason an accurate time drive must be furnished.

Power from any suitable source, such as a motor shown diagrammatically at 35 drives through the differential mechanism 36 the sprocket chain 37 which in turn drives the gears 38 and 39, the latter being mounted upon the shaft 40 positioned longitudinally of the machine and having mounted thereon a plurality of bevel gears 41, 42, 43, 44, 45 and 46. These bevel gears in turn mesh with bevel gears 47, 48, 49, 50, 51 and 52 mounted upon the shafts of the respective units, the details of which are purposely omitted as their relation to the rolls is obvious from Figs. 1 and 2.

In the modified form of construction in place of slitting the sheet after passing the corrugated roll shown in Fig. 4, the upper sheet is perforated by the perforating members shown at 53 mounted in place of the slitting knives on the roll 11. When the perforating mechanism is used, a sheet is made such as that shown in Fig. 7 with perforations of any desired configuration, according to the shape of the perforating members upon the ridges or corrugations of the upper sheet.

When the modified form of construction is employed, it is necessary to remove the punched out disks from the lower roll.

These disks find their way from the sheet through the ducts 54 leading to a cylindrical chamber 55 in the center of the roll 11. Here a screw conveyor 56 driven from a sprocket chain 57 from the upper roll expels the disks as they are punched out from the center chamber 55.

The sheet after cut into units of desired sizes by the cutting roll 31 is fed by means 10 of conveyor belts 58 running from the pulley 59 mounted on the shaft 60 to any desired storage where they are removed and bundled or stacked to be shipped.

The sheet produced and the process herein 15 explained, has to do with the making of a plaster board or sheeted lath to which may be applied plaster, the combination to be used in building construction.

It is understood that a corrugated sheet 20 produced in this manner may be used for innumerable purposes, as hereinbefore suggested.

Heretofore, it has been common practice 25 to produce corrugated sheeted material by means of rolls, but it is thought to be novel to corrugate a sheet in the manner shown, with an endless corrugating element which carries the corrugated sheet along, and prevents the stretching or elongation of the corrugation during subsequent operation of the sheet.

A further advantage of the sheet is the 30 rigidity produced by the applying of a base material coated with an adhesive substance which may be fixedly united or combined 35 with the corrugated upper sheet. The adhesive substance utilized in uniting the sheets may be of a waterproofing character such as bitumen, pitch or asphalt, or it may 40 comprise simply glue or sizing material such as that commercially used at the present time.

The purpose for which the material is to 45 be used, will determine the character of the adhesive substance best adapted to the use to which it is to be put, and also the character of the sheeted material together with its stiffness and rigidity. These factors will 50 necessarily be variables according to the uses to which the product is to be put.

I claim:

1. A process of making a corrugated board consisting in forming a sheet into corrugations, making transversely extending incisions through the sheet at predetermined longitudinal intervals on the crests of said corrugations, coating a second sheet with an adhesive substance, pressing the base of the corrugations into contact with

the underlying sheet to cause an amalgamation thereof with the corrugated sheet.

2. A process of making a corrugated board consisting of forming a sheet into corrugations, making incisions through the sheet at predetermined intervals, and substantially on the crests of said corrugations, coating a second sheet with an adhesive, and pressing the base of the corrugations into contact with the underlying adhesive coated sheet to cause an amalgamation thereof.

3. Process of making a corrugated board consisting in forming a sheet into corrugations, making incisions through the corrugated sheet at predetermined intervals and substantially on the crests of said corrugations, coating a second sheet with an adhesive substance, uniting the adhesive coated second sheet with the corrugated sheet to form a unitary structure.

4. Process of making a corrugated board 60 consisting in forming a sheet into corrugations, making incisions through the corrugated sheet at predetermined intervals and substantially on the crests of said corrugations, coating a second sheet with an adhesive substance, uniting the adhesive coated base sheet with the corrugated sheet to form a unitary structure, and severing the sheets 65 into units.

5. A process of making corrugated board 70 which consists in forming a sheet into corrugations, making transversely extending groups of incisions through the sheet at suitable longitudinal intervals and substantially in the crests of said corrugations, and 75 coating the second sheet with an adhesive, uniting the corrugated sheet with the adhesive coated sheet to form a unitary structure, and continuously moving both sheets 80 of which the board is made.

6. A process of making a corrugated board, consisting in corrugating a sheet, making incisions thru the sheet at predetermined points in the corrugations, coating a second sheet with an adhesive substance, and 100 uniting the adhesive coated second sheet with the corrugated sheet to form a unitary structure.

7. A process of making a corrugated board, consisting in corrugating a sheet, 110 making incisions thru the sheet at predetermined points in the corrugations, coating a second sheet with an adhesive substance, and uniting the adhesive coated second sheet 115 with the corrugated sheet to form a unitary structure, pressing the incised portions into the surface of the base sheet.

HARRY A. CUMFER.
